UNITED STATES PATENT OFFICE.

WILLIAM OATES, JR., OF LEAD, SOUTH DAKOTA.

COOLING SYSTEM.

1,398,199.

Specification of Letters Patent.

Patented Nov. 22, 1921.

Application filed May 17, 1920. Serial No. 382,167.

To all whom it may concern:

Be it known that I, WILLIAM OATES, Jr., a citizen of the United States, residing at Lead, in the county of Lawrence and State 5 of South Dakota, have invented new and useful Improvements in Cooling Systems, of which the following is a specification.

This invention relates to an attachment for cooling systems of automobiles and the 10 like and the principal object of the invention is to provide means whereby the water capacity of the cooling system may be increased and the cooling surfaces enlarged.

Another object of the invention is to make 15 the attachment easily applicable to the cooling systems now in use and also to place the attachment where it will receive the air from the fan.

This invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying 30 drawings wherein like characters denote like or corresponding parts throughout the several views, and in which:—

Figure 1 is a diagrammatic view showing the device in use.

Fig. 2 is a sectional view through the device itself.

Fig. 3 is a section on line 3—3 of Fig. 2.

As shown in Fig. 1 the device, indicated generally at 1, is connected with the pipe line leading from the bottom of the radiator 2 to the inlet of the water jacket of the 40 motor, shown at 3. The device is made in the form of a cylindrical drum with the inlet nipple 4 and the outlet nipple 5 project-

ing from the ends, said nipples being arranged adjacent one side of the drum. Baffle plates 6 are arranged in said drum 45 so as to give the water a zig zag path as it passes through the drum. The lower plates have small openings 7 in their lower edges for permitting the water to drain from the drum when the cooling system is drained. 50

As will be seen the drum is placed where it will receive the air from the cooling fan so that the water passing through said drum will be cooled by said air. As the drum is made of considerable size the quantity of 55 water used in the cooling system is considerably increased thus preventing overheating of the motor in hot weather or unusual conditions.

It is thought from the foregoing description that the advantages and novel features of my invention will be readily apparent. 60

I desire it to be understood that I may make changes in the construction and in the combination and arrangement of the 65 several parts, provided that such changes fall within the scope of the appended claim.

What I claim is:—

In combination with a water system of an internal combustion engine, a cylindrical 70 drum, an inlet nipple and an outlet nipple projecting from the end, said nipple being arranged adjacent one side of the drum, an upper baffle plate arranged in said drum so as to give the water a zig zag path as it 75 passes therethrough, lower plates having openings formed in their lower edges for permitting the water to drain from the drum when the cooling system is drained, said drum being connected with the pipe 80 line leading from the bottom of the radiator to the inlet of the water jacket of the motor.

In testimony whereof I affix my signature.

WILLIAM OATES, JR.
